To all whom it may concern:

Be it known that I, Charles D. Palmer, a citizen of the United States and residing in Brooklyn, county of Kings, and State of New York, have invented a new, original, and ornamental Design for a Manual Tubing Cutter, of which the following is a specification, reference being had to the accompanying drawing, forming a part thereof.

Fig. 1 is a top plan view of a manual tubing cutter, showing my new design.

Fig. 2 is a side elevational view of the same.

Fig. 3 is a front end view of the same.

Fig. 4 is a bottom view of the same.

Fig. 5 is a rear end view of the same.

I claim:

The ornamental design for a manual tubing cutter, as shown.
